Specification for Design.

Patented June 24, 1913.

Application filed April 6, 1912. Serial No. 689,076. Term of patent 14 years.

To all whom it may concern:

Be it known that I, PETER A. SELIG, a citizen of the United States, residing at Chicago, in the county of Cook and State of Illinois, have invented a new, original, and ornamental Design for Chair-Seats, of which the following is a specification, reference being had to the accompanying drawing, forming part thereof.

My said design consists in an ornamental design for a chair seat.

The figure is a perspective view of a chair seat showing my new design.

I claim:

The ornamental design for a chair seat, as shown.

PETER A. SELIG.
